(57) **CLAIM**

The ornamental design for a camera boom device, as shown
and described.

DESCRIPTION

FIG. 1 is a perspective view of my camera boom device;
FIG. 2 is a top view thereof;
FIG. 3 is a right side elevational view thereof, the left side
elevational view being a mirror image thereof;
FIG. 4 is a bottom view thereof;
FIG. 5 is a front elevational view thereof;
FIG. 6 is a rear elevational view thereof;
FIG. 7 is an enlarged partial right side view of a portion of
FIG. 3 in a circle labeled “FIG. 7”;
FIG. 8 is an enlarged partial front view of a portion of FIG.
5 in a circle labeled “FIG. 8”;
FIG. 9 is an enlarged partial rear view of a portion of FIG.
6 in a circle labeled “FIG. 9”;
FIG. 10 is a perspective view of an alternative embodiment;
FIG. 11 is a top view of the alternative embodiment;
FIG. 12 is a right side elevational view thereof, the left side
elevational view being a mirror image thereof;
FIG. 13 is a bottom view of the alternative embodiment;
FIG. 14 is a front elevational view of the alternative embodiment;
FIG. 15 is a rear elevational view of the alternative embodiment;
FIG. 16 is an enlarged partial right side view of a portion of
FIG. 12 in a circle labeled “FIG. 16”;
FIG. 17 is an enlarged partial front view of a portion of FIG.
14 in a circle labeled “FIG. 17”; and,
FIG. 18 is an enlarged partial rear view of portion of FIG.
15 in a circle labeled “FIG. 18”.
